UNITED STATES PATENT OFFICE.

JOSEPH ROBERT DOOLEY, OF MOBILE, ALABAMA.

CROSSTIE.

1,343,814.

Specification of Letters Patent. Patented June 15, 1920.

Application filed November 26, 1919. Serial No. 340,811.

To all whom it may concern:

Be it known that I, JOSEPH R. DOOLEY, a citizen of the United States, and a resident of Mobile, county of Mobile, State of Alabama, have invented a new and useful Improvement in Crossties, of which the following is a full, clear, and exact description.

The present invention relates to cross-ties and has particular reference to an improved 10 means of supporting track rails thereon.

The primary object of the invention is to provide an improved construction of cross ties whereby rails may be supported and mounted thereon, and although the rail 15 mounting *per se* may become defective on account of wear and tear it will not necessitate replacing a cross tie, to which end it is proposed to so construct the tie as to enable the removable rail supporting section or 20 block to be used which may be removed from the cross tie and replaced in a most practical manner.

The accompanying drawings illustrate the salient features of the invention, and in 25 which—

Figure 1 is a plan view of a tie showing a rail as supported thereon.

Fig. 2 is a side elevation of a tie showing the rail as associated therewith.

Fig. 3 is a sectional view on the line 3—3 of Fig. 2.

Fig. 4 is a perspective view of the rail plate with the preferred form of mounting means.

Fig. 5 is a cross section of the rail supporting section or block.

Fig. 6 is a plan view of a modified form of the rail plate.

Fig. 7 is a side elevation of a tie showing 40 the rail as associated therewith and the use of the rail plate referred to in Fig. 6.

Fig. 8 is a perspective view of the rail plate as proposed in Figs. 6 and 7.

Fig. 9 is a cross sectional view through a 45 tie and the rail supporting section block, and

Fig. 10 is a perspective view of one means of anchoring the rail supporting section or block on the tie.

The cross tie proposed by this invention 50 is applicable to railroads or any other track system, and although it would be referred to as used in connection with a track system in which the cross ties extend from one rail to another, and that the same may be 55 of wood, it is not to be considered as neces-

sarily limited to this use or construction, as in many instances the advantages of the invention can be realized with a short cross tie, or rather one which does not extend from one rail to another, but embedded in 60 concrete or a like supporting base, and of a length only sufficient to support one rail of a track; then again the tie *per se* may be constructed of metal or any other suitable material.

In putting the invention into use it would seem desirable to shape the tie *per se* 1, with a relatively large base with the side and end walls thereof tapering to provide a more or less narrow face 2, the face 2 being tapered on both sides of the rail supporting location so that the intermediate face of the tie between the rails will be very much narrower than that portion of the face immediately around the rail.

It is to be readily appreciated that in rail road systems, particularly where the traffic is heavy, considerable difficulty is experienced with rail cut. The present practice is to use a rail plate on the tie which will 80 offer a relatively large support to the rail on the tie, and to some extent do away with this rail cut, however this is in no way a practical solution of the problem and it often happens that while the tie may be in a more or less perfect state of preservation it must 85 be discarded on account of the rail cut. This involves considerable expense and the invention therefore has for one object to provide means whereby the entire tie need 90 not be replaced but only that portion of the tie which has been injured by the rail cut, and the other conditions which injure the tie at the locality of supporting the rail thereon.

To accomplish this object it is preferred to construct a tie with a removable rail supporting section or block such as 3, with the face 2 of the tie provided with a pocket made to receive the section or block 3. In 100 order that the section or block 3 may be capable of lateral removal when the rail has been disconnected therefrom and without removing the rail from the ties, a pocket is produced with concaved undercut end 105 walls 4 and 5, one of which, namely, the wall 4 having a curvature exceeding that of the wall 5, while the latter is eccentric to the arc of the wall 4 and inclined so that the section or block 3 may be laterally intro- 110

duced into the pocket by first presenting the end which conforms to the wall 4 into the pocket adjacent that wall and by an angular movement in an anti-clockwise direction slide the opposite side which conforms to the wall 5 into place. The pocket is also dovetailed or undercut at the ends to prevent vertical or upward displacement of the section or block 3. The ends of the block 10 or section 3 are also circular, being convex and conical or inclined downwardly to fit the undercut concaved walls 4 and 5. That is, it will be noted from Figs. 1 and 6 that the section or block 3 has one end as well 15 as the corresponding concaved wall of the recess of the pocket, cut on an arc, the center or axis of which is located intermediately of the sides of the tie and the radius of which is less than the radius of the arc at the opposite end of the pocket or block, while the center of the latter is disposed to one side of the longitudinal center of the tie whereby the arc is eccentric to the arc at the opposite end in order that the block may 20 be inserted or displaced from one side only and is limited in its engagement in the opposite direction so that it may be retained in position as will now be described.

In order that the section or block may be 30 normally maintained in the pocket, a suitable clamping rod or bolt 6, which is passed through the transverse opening 7 in the block, may be employed. This rod or bolt 6 may be constructed in some instances with 35 a head 8 which may engage the side of the tie, and with its opposite end 9 threaded to receive a nut 10 which may be screwed up on the threaded end to engage the side of the block 3 and the side of the tie so as to overlap the edges of the block and the tie. As 40 shown in Fig. 3 a locking device such as 11 may be used to prevent the nut 10 from becoming loose. This form of bolt or rod 6 need not be controlling in every instance, 45 for as shown, in Figs. 9 and 10 this bolt or rod may take the place of a flat strip 6¹ which is received in a like shaped groove in the bottom of the section or block 3 and made to have its opposite ends 8¹ and 9¹ bent 50 downwardly and upwardly, respectively so as to overlie the side of the tie and side of the section block 3 respectively. It may be desirable to countersink the sides of the tie and the sides of the section block to receive 55 the ends 8¹ and 9¹ of the strip 6¹ so as to more or less confine the same.

It would seem desirable to employ a rail plate in connection with this form of tie just as in the conventional track construction, but in this case to depart from the usual manner of using spikes as a medium of fastening the rail to the tie, at least in so far as concerns the preferred arrangement contemplated by the invention. According

to this preferred form of rail plate and the 65 manner of using the same in association with the rail supporting block 3, the block is provided at diagonally opposite corners with openings which extend into the block from top to bottom and are made to receive the rail base engaging means comprising the vertically presented claw fingers 12. The base of the section block 3 is provided with countersunk openings to receive the bent 75 ends 12¹ of the claw fingers 12 so that the same may be securely anchored in the section block. The rail base engaging ends of these fingers are provided with claws so that the rail may be maintained against displacement.

The rail plates in their preferred form are made with slots or openings 14 arranged at diagonally opposite corners of the plate and reinforced by the piece 14¹. The claw fingers 12 are passed through the openings 14 85 with the plate inserted between the rail and the supporting face of the sections or blocks. One end of the section or block is rabbeted with one end of the plate bent downwardly as at 15 to engage the rabbeted edge of the 90 block.

Referring to the plate shown in Figs. 6, 7, and 8 the plate is constructed with an upwardly presented member 16 having a slotted opening made as at 17 between the member and the plate in which is received the base of the rail with the inwardly disposed end of the member bearing against the web of the rail. This may be used with the claw fingers 12 to provide an auxiliary rail engaging means such as a brace or the like. From the above it will be readily seen that any of the blocks 3 may be removed and replaced by a new one without necessitating the removal of the tie *per se* from the track 105 and without the necessity of driving spikes after the block has been placed in position. As the claw fingers which take the place of the spikes are carried by the block, all that is necessary is to place the section of the block 110 with the rail plate carried thereon in place as above described and by inserting the rod 6 or the strip 6¹. Of course if desirable the blocks or sections 3 may be used with spikes or with any other retaining means instead 115 of the rod 6 or the strip 6¹. Then again various other forms of rail plate may be used but the arrangements shown and described are considered preferable in reducing the invention to practice.

Having thus described my invention what I claim as new and desire to secure by Letters Patent is as follows:—

1. A cross tie embodying in its construction, a removable rail supporting section, 125 said tie having a pocket with arcuate end portions, and said removable supporting section having ends coöoperating with said end

portions to permit pivotal application or displacement of the supporting section, and interlocking means between the tie proper and the supporting section for securing the latter in position.

2. A cross tie embodying in its construction, a removable rail supporting section, the tie having a pocket with arcuate end portions and the removable supporting section having ends coöperating with said end portions to permit pivotal application or displacement of the supporting section, interlocking means between the supporting section and the tie proper for retaining the supporting section in position in the pocket, and rail securing means carried by the supporting section and retained in position thereby.

3. A cross tie having a pocket provided with a concaved wall, the center of the arc of which is located substantially intermediate of the sides of the tie, the opposite end wall being curved eccentrically to the first-named end wall, a supporting and securing block conforming to said walls and adapted for lateral application and displacement, and means for detachably securing said block in position.

4. A cross tie having a pocket provided with a concaved wall, the center of the arc of which is located substantially intermediate of the sides of the tie, the opposite end wall being curved eccentrically to the first-named end wall, a supporting and securing block conforming to said walls and adapted for lateral application and displacement, said block being limited in its movement into the pocket, the ends of the pocket being undercut and the ends of the block being inclined to conform thereto whereby the block is held from vertical displacement, and rail base engaging means carried by the block and retained between the same and the tie at the bottom of the pocket.

5. A cross tie having a pocket provided with a concaved wall, the center of the arc of which is located substantially intermediate of the sides of the tie, the opposite end wall being curved eccentrically to the first-named end wall, a supporting and securing block conforming to said walls and adapted for lateral application and displacement, said block being limited in its move-

ment into the pocket, the ends of the pocket being undercut and the ends of the block being inclined to conform thereto whereby the block is held from vertical displacement, means for securing the block in position in the pocket and against displacement, said block being of penetrable cushioning material, such as wood, and anchoring means carried by the block.

6. The combination with a tie provided with a recess in the top thereof formed with concaved end walls, one of which is inclined with respect to the other; of a block having its ends conforming thereto and fitting in said recess, said block being adapted for lateral displacement by a pivotal movement from one end, a rail plate mounted on the block, the block having a recess and the plate having a flange engaging said recess, rail engaging means carried by the plate and block, and means to secure the block in the recess, said means overlying the tie and block.

7. A cross tie having a portion of its rail supporting face cut away to provide a pocket and made to receive a rail supporting block, means for normally maintaining said block in said pocket, the pocket being cut with concaved end walls, the curvature of one wall of the pocket exceeding that of the other wall and the ends of the rail supporting block conforming to the end walls of the pocket whereby the rail supporting block is capable of lateral swinging displacement or removal from the pocket.

8. A cross tie having a pocket made to receive a rail supporting section or block, the end walls of the pocket being concaved undercut in shape with the ends of the sections or blocks made to conform therewith, the curvature of one wall of the pocket exceeding that of the other wall, whereby the section or block may be received in the pocket by a lateral rotating engagement, means carried by the section or block for engaging the rail and anchoring the same to the section or block; a rail plate providing a bearing surface between the section or block and the base of the rail, and means for normally maintaining the section or block in said pocket with the rail rigidly supported thereon.

JOSEPH ROBERT DOOLEY.
